CLAIM

The ornamental design for a combined slide and rail for a furniture cabinet, as shown and described.

DESCRIPTION

FIG. 1 is a front perspective view of a combined slide and rail for a furniture cabinet showing our new design;

FIG. 2 is a front elevation view thereof;

FIG. 3 is a top plan view thereof, the bottom view being a mirror image;

FIG. 4 is a rear elevation view thereof;

FIG. 5 is a right end view thereof; and,

FIG. 6 is a left end view thereof.
